Primary Examiner — Mary Ann Calabrese(74) *Attorney, Agent, or Firm* — Mark B. Eisen; Dimock Stratton LLP(57) **CLAIM**

The ornamental design for a hand waver, as shown and described.

DESCRIPTION

FIG. 1 is a front elevational view of a first embodiment of the hand waver.

FIG. 2 is a rear elevational view of the hand waver of FIG. 1.

FIG. 3 is a right side elevational view of the hand waver of FIG. 1.

FIG. 4 is a left side elevational view of the hand waver of FIG. 1.

FIG. 5 is a top plan view of the hand waver of FIG. 1.

FIG. 6 is a bottom plan view of the hand waver of FIG. 1.

FIG. 7 is a front elevational view of a further embodiment of the hand waver.

FIG. 8 is a rear elevational view of the hand waver of FIG. 7.

FIG. 9 is a right side elevational view of the hand waver of FIG. 7.

FIG. 10 is a left side elevational view of the hand waver of FIG. 7.

FIG. 11 is a top plan view of the hand waver of FIG. 7; and,

FIG. 12 is a bottom plan view of the hand waver of FIG. 7.

The slit shown in broken lines in FIGS. 6 and 12 does not form part of the claimed design.
